INTERNAL COMBUSTION ENGINE

Edwin S. Hall, New Haven, Conn.

Application March 27, 1939, Serial No. 264,440

17 Claims. (Cl. 123—58)

This invention relates to internal combustion engines and its salient object is to provide a most compact engine of minimum bulk and weight. Compactness and minimum weight are best attained with those engine types which have small crankcase volume, as for example, the radial engines in which the cylinders face each other around a common mechanism, or the opposed cylinder engines or the barrel type engines in which similar groups of cylinders face each other with the engine mechanism between them. This invention may be conveniently described as applied to the normal barrel engine with cylinders parallel to the shaft in two similar groups facing each other with the rotary-reciprocating mechanism between them, but it is applicable also to other types of engines such as those mentioned above.

An object of this invention is to provide a shorter and more compact parallel cylinder engine of less specific weight, and to provide means for reducing the length and weight of such an engine by about 25% under what has been possible.

25 In a parallel cylinder engine of the normal type, bearing loads are much lower and other mechanical conditions much superior if the engine is run on the two-stroke cycle. For two-stroke operation, uniflow scavenge is preferred, 30 with intake ports at one end of the cylinder and exhaust ports at the other end. Thermal conditions in the pistons are best if the pistons control the intake ports while the exhaust ports are controlled by valves. An object of this invention is 35 to provide a uniflow two-stroke engine with improved sleeve valves and sleeve valve operating means, at the same time using the sleeve valves to permit shorter piston members than would otherwise be possible for a given piston stroke, 40 thereby shortening the engine and reducing its weight. Another object is to reduce engine weight and size still more by using the sleeve valves as cylinder liners, dispensing with the need of fixed liners and separate valve systems.

45 Another object is to provide the piston members with oil control rings which never pass over the piston-controlled ports, and at the same time having shorter piston members than would be possible, even without oil control rings, if sleeve 50 valves were not used. The foregoing objects are attained by using single sleeve valves in a two-stroke parallel cylinder engine, the sleeves having strokes longer than usual and timed almost in time with the piston strokes, so that the sleeves, 55 as they move outward from the cylinders, retain

the piston rings in operable position after the rings have passed beyond the mouths of the cylinders themselves, thereby permitting the piston members to be much shorter, resulting in a shorter and lighter engine, the reduction amounting ordinarily to about 25%.

5 Another object is to provide sleeve valves for a parallel cylinder engine with driving means operably connecting the sleeves with the rotary-reciprocating engine mechanism, whereby the 10 sleeve valves are given strokes somewhat shorter and preferably slightly advanced in timing relative to the strokes of the pistons.

Another object is to provide sleeve valves which extend thru both coaxial cylinders in a normal 15 parallel cylinder engine, the sleeves serving not only as valves and liners for the cylinders, but as crosshead guides for the piston members. A further object is to provide mechanisms for driving such combined sleeve valve and crosshead guide 20 units.

Another object is to provide individual sleeve valves for the several cylinders of a parallel cylinder engine, so that the port timing can be suited to each cylinder, with means for driving the sleeves 25 from the engine shaft independently of the rotary-reciprocating engine mechanism. Another object is to provide a cam mechanism for driving such individual sleeve valves so as to make possible giving each sleeve the optimum movement relative to piston movement, for the best conditions of port timing and wear. Another object is to provide improved cam driving mechanisms for 30 sleeve valves.

In parallel cylinder engines of the wabbler 35 type, where the rotary-reciprocating mechanism comprises a wabbler mounted on bearings inclined to the shaft, some means of restraining the rotation of the wabbler or of controlling its float is desirable. An object of this invention is 40 to provide means for driving sleeve valves directly from the wabbler which driving means will function also to control the wabbler float, preferably permitting the wabbler to have its true geometric motion. Another object is to provide means for 45 eliminating excessive clearances in sleeve valve operating mechanisms in a parallel cylinder engine.

In any two-stroke engine, for best economy, fuel injection should be used. An object of this 50 invention is to provide an improved fuel injection system especially suited to a parallel cylinder engine.

These and other objects of the invention and the means of attaining them will be more clear 55

from the following description in connection with the drawings in which

Fig. 1 is a longitudinal section of a parallel cylinder engine having a wabbler mechanism and individual single sleeve valves, one in each cylinder, the valves being driven by cam mechanisms independent of the wabbler mechanism;

Fig. 2 is a radial or plan view, in section, of a reciprocating member of the mechanism shown in Fig. 1;

Fig. 3 is a partial transverse section of the wabbler mechanism of Fig. 1 taken thru the mid-section of the reciprocating member of Fig. 2;

Fig. 4 is a longitudinal section of another parallel cylinder engine having a wabbler mechanism and tubular members each serving as sleeve valves for the cylinders of each pair and as a crosshead guide for the reciprocating piston member, these tubular members being driven directly from the wabbler, and the driving mechanism serving also to control the wabbler float and maintain the geometrically correct movement of the wabbler;

Fig. 5 is a radial or plan view, in section, of one of the tubular members of Fig. 4, with the crosshead portion of the reciprocating member in place;

Fig. 6 is a transverse section thru the mechanism of Fig. 4, showing portions of the driving arrangements of the tubular members;

Fig. 7 is an alternate construction of the mechanism for driving the tubular valve and crosshead guide members directly from the wabbler while maintaining the wabbler float;

Fig. 8 is a longitudinal section of a parallel cylinder engine of the cam type, having a cam and roller rotary-reciprocating mechanism and sleeve valves, the latter being also crosshead guides for the piston members and cylinder liners, driven by another cam mechanism; and

Fig. 9 is a partial transverse section taken on the line 8-9 of Fig. 8.

Referring to Figs. 1-3 of the drawings, shaft 10 is mounted in bearings 11 and 12 in cylinder blocks 13 and cylinder covers 14 respectively. Casing member 15 is interposed between and bolted to cylinder blocks 13. Formed in cylinder blocks 13 are cylinders 16 with their axes parallel to shaft 10. Shaft 10 is axially located by slipper thrust bearing 20. Swashplate 21 is fixed on shaft 10 in any suitable manner as by the splines and conical wedge pieces shown.

Wabbler 24, comprising two similar members bolted together, is operably mounted with suitable bearings on swashplate 21. The two parts of wabbler 24 are solids of revolution, their peripheral surfaces 25 and 26 being cylindrical and the intervening surfaces 27 being plane.

Wabbler arm assemblies are spaced about wabbler 24, each assembly comprising a pedestal member 28, cap 29, wristpin bushing 30, and capscrews 31, together with wristpin 32 locked in radial 33 by set screws 34. Pedestal 28 has inner surfaces cylindrical and plane conforming respectively to cylindrical surfaces 25 and 26 and plane surfaces 27 of wabbler 24, and, as shown in Fig. 1, are bifurcated to straddle the inner portions of the two members of wabbler 24 to assist in holding them together and for additional strength of the arm and its attachment to the wabbler. Capscrews 31 clamp wristpin bushing 30 between cap 29 and pedestal member 28, holding them securely to wabbler 24. Bushing 30 is free to rock and reciprocate on wristpin 32 as required by the operation of

the mechanism, its axial movement being finally checked by the cushion action of loose fitting dashpots 35 formed in radial 33.

Radial 33 is operable in bore 36 in crosshead 37. Crosshead 37 is operable in cylindrical bore 18 formed in casing member 15 coaxial with cylinders 16. Pistons 17 are clamped to crosshead 37 by clamps 38 and screws 39.

Interposed between cylinders 16 and pistons 17 are sleeve valves 19 serving also as cylinder 10 liners. Sleeve valves 19 are engaged and operated by forked members 190 whose stems 191 pass thru and are operable in bores in cylinder blocks 13 and are clamped to roller carriers 192 by screws 193. Rollers 195, integral with their pins, are operably mounted in half-journal bearings formed in roller carriers 192 and operably engage cam 194 which is fixed on shaft 10.

Sleeve valves 19 are provided with intake ports 22 opening from the air chambers 131 in cylinder blocks 13 which are fed from suitable blowers or other means. Ports 22 are overrun and controlled by pistons 17. The head ends of sleeve valves 19 are bevelled internally to weaken them sufficiently so that they will expand under cylinder pressure to seal against leakage from combustion chambers 161 into exhaust ports 23.

Cylinders 16 in cylinder blocks 13 are closed by individual cylinder heads 160 which form, with the heads of pistons 17, combustion chambers 161. Fuel pumps 162 are arranged radially relative to shaft 10 and are operated by cam 164 which is fixed on shaft 10. Each fuel pump 162 is inserted in a bore in cylinder cover 14 and extends outward toward one of the cylinder heads 160. Fuel nozzle 166 passes thru the body of fuel pump 162 and into cylinder head 160 with suitable packing nuts so that fuel may be delivered directly from fuel pump 162 to nozzle 166 under high pressure without any piping.

Operation of the engine on the two-stroke compression ignition cycle is well understood. Fuel injected thru nozzle 166 into the charge of air in combustion chamber 161 which charge has been heated by compression, ignites and the combustion drives the piston outward. Sleeve valves 19 are timed to open exhaust ports 23 well in advance of the opening of intake ports 22 by the pistons 17, to permit the exhaust to reduce the pressures in the cylinders to less than that in the air chambers when intake ports 22 open. Similarly exhaust ports 23 are closed before pistons 17 close intake ports 22, to permit supercharging the cylinders to blower pressure. Reciprocation of the piston members is accompanied by rotation of shaft 10 by the action of the wabbler mechanism in a well-known manner. The construction of wabbler 24 and associated parts is such that practically no torque reaction can be imposed on the wabbler, the wabbler normally tending to float in the middle of its rotational freedom. Should wabbler 24 tend to go to the limit of its rotational freedom, dashpots 35 may serve as cushions of oil and air to prevent knocking. Rotation of shaft 10 also causes rotation of cams 194 which coat with rollers 195 and associated parts to drive sleeve valves 19. At the right of Fig. 1, both intake ports 22 and exhaust ports 23 are shown closed, but at the left, intake ports 22 are shown open, and of course, with the sleeve valve 19 withdrawn, exhaust ports 23 will also be open, piston 17 being at "bottom center," in which position sleeve 19 serves to maintain the rings of piston 17 in operable position, even the lowermost oil

control ring being retained altho drawn several inches beyond and out of the mouth of cylinder 16. At the right of Fig. 1, it may be noted that this oil control ring never passes above ports 22.

5 Referring to Figs. 4-7, shaft 40 is mounted in bearings 41 and 42 in cylinder blocks 43 and covers 44 respectively. Casing member 45 is interposed between and bolted to cylinder blocks 43. Formed in cylinder blocks 43 are cylinders 10 46 with their axes parallel to shaft 40.

15 Swashplate 51 is fixed on shaft 40 in any suitable manner. Wabbler 54, comprising two similar members bolted together, is operably mounted with plane and cylindrical bearings on swash-
plate 51. The two parts of wabbler 54 are solids of revolution, their peripheral surfaces 55 and 56 being cylindrical and the intervening surfaces 57 being plane. Wabbler arm assemblies radiate from and are spaced about wabbler 54, each 20 assembly comprising a pedestal member 58, cap 59, wristpin bushing 60, and capscrews 61, together with wristpin 62 carried by and locked in radial 63. Pedestal member 58 has inner surfaces cylindrical and plane conforming respectively to cylindrical surfaces 55 and 56 and plane surfaces 57 of wabbler 54, and as shown in Fig. 4, are bifurcated to straddle the inner portions of the two members of wabbler 54 to assist in holding them together, and for additional strength 25 in the attachment of the wabbler arm to wabbler 54. Capscrews 61 clamp wristpin bushing 60 between cap 59 and pedestal member 58, holding them securely to wabbler 54. Bushing 60 is free to rock and reciprocate on wristpin 62, 30 as required by the operation of the mechanism. Radial 63 is operable similarly in bore 66 of crosshead 67. Pistons 47 are clamped to crosshead 67 by clamps 68 and screws 69.

35 For each reciprocating member comprising two pistons 47 clamped to a crosshead 67, an integral tubular member 49 forms a sleeve valve and cylinder liner for each piston 47 and a crosshead guide for crosshead 67, the tubular member 49 being operable in both opposite cylinders 46 of cylinder blocks 43 and extending from one to the other within casing 45. Tubular members 49 are driven directly from wabbler 54 by means of an operating mechanism comprising slippers 541 mounted in recesses 540 in wabbler 54 and in 40 cups in plungers 542 which plungers 542 are adjustable within bores in plungers 543, these latter plungers 543 being reciprocable in bores in cylinder blocks 43 and having arms 491 operably engaging tubular members 49 to drive the same. 45 Operating clearances in the operating mechanism connecting wabbler 54 with tubular members 49 are kept at a minimum by means of springs 544 and ball check valves 545 cooperating with oil pressure from the engine lubrication system supplied thru suitable conduits 546 from main bearings 41.

50 In Fig. 7 an alternate design of the sleeve valve operating mechanism is shown. Plungers 543 with arms 491 are the same as those shown in Fig. 4, but inner plungers 642 are provided with offset terminal discs 640 operably engaging sockets 540 in wabbler 54. During operation of the mechanism, plungers 642 and terminal discs 640 rotate at the same speed as shaft 40.

55 Operation of the engine of Figs. 4-7 is similar to that of Figs. 1-3. Tubular members 49 serve as sleeve valves, as cylinder liners, and as crosshead guides for the piston members. With their operating mechanisms in the intercylinder 60 planes, the reciprocation of tubular members 49

lead that of the piston members by twenty degrees of shaft rotation, and since the axes of plungers 542 and 543 are on a circle of substantially half the radius of the cylinder pitch circle, the length of stroke of tubular members 49 is 5 substantially half that of the piston members. Whenever the driving load is momentarily off from one of the driving mechanisms comprising a slipper 541, plunger 542 and plunger 543 and associated parts, spring 544 acts to elongate the 10 plunger member taking up any clearance, oil entering thru check valve 545 to substantially maintain the new length of the plunger member under load, any excessive stress which might result being relieved by slight leakage of oil trapped 15 between plungers 542 and 543.

20 Slippers 541 or offset terminal discs 640 could operate directly on the plane outer faces of wabbler 54, but by mounting them in recesses 540 they may act also to control the wabbler motion, 25 confining it to its geometrically correct movement, dispensing with the necessity for dashpot cushions 35 shown in Figs. 1-3. Slippers 541, as they work around in recesses 540, may rotate more or less in their cups in plungers 542; terminal discs 25 640 and their plungers 642 must rotate in plungers 543 as the wabbler operates. If the wabbler mechanism were of any other type than that shown, control means of this sort might be inadequate because the engine torque reaction 30 would be upon them, but with the mechanism shown, the wabbler control system must control only incidental tendencies of the wabbler to depart from its true motion, caused for the most part by friction in the wabbler bearings. 35

35 Referring to Figs. 8 and 9, shaft 80 is mounted in bearings 81 and 82 in cylinder blocks 83. Casing member 85 is interposed between and bolted to cylinder blocks 83. Formed in cylinder blocks 83 are cylinders 84 with their axes parallel to shaft 80; cylinders 84 formed in casing member 85 are coaxial with cylinders 86 and of somewhat larger bore.

40 Tubular member 99 is operable within cylinders 84 and 86 as movable cylinder liners, crosshead guide, and sleeve valves for the piston member comprising a pair of pistons 93 and connecting bridge portion. Cam member 87 is fixed on shaft 80 in any suitable manner and has a pair of cams 88 and another pair of cams 89. 45 Cams 88 engage rollers 90 integral with their pins 91 which pins 91 are operably mounted in half-journal bearings formed in pistons 93. Cams 89 engage rollers 97 operably mounted in tubular member 99. Key 94 is fixed in the central or 50 bridge portion of the piston member, and is operable in slots 95 and 96 formed in tubular member 99 and casing member 85 respectively to prevent rotation of the piston and sleeve valve members. 55

60 Rollers 90 have their axes inclined for the double purpose of permitting the rollers to reach inward to a cam of smaller diameter, thus permitting a thicker and more rigid bridge portion for the piston members and tubular members 99, 65 and of introducing an outward radial component into the side thrust on the piston members to avoid beam loading thereon, the resultant piston side thrust being toward ample bearing area of the bridge portion of the piston member and of 70 the tubular member where the latter bears in cylinder 84 in casing member 85. The central or bridge portions of tubular members 99 are somewhat thicker than their sleeve valve portions, 75 their exteriors conforming to the respective bores 75

of cylinders 84 and 86. Moreover, the central or bridge portions of tubular members 99 are cam ground externally, with inward reaching portions to provide mountings for the rollers 97.

5 Operation of an engine with the mechanism shown in Figs. 8 and 9 is similar to that of the engine of Figs. 1-3. Piston thrust is converted into shaft rotation by the cam and roller mechanism instead of by a wabbler mechanism, and 10 similarly, tubular members 99 are driven by cam and roller mechanism comprising cams 89 and rollers 97.

An engine with the cam and roller mechanism is normally somewhat shorter and of less weight 15 than an engine with the wabbler mechanism, but the reduction in engine length and weight resulting from the adoption of sleeve valves having unusually long strokes timed substantially with the piston strokes, is proportionally about 20 the same. In a specific design, the length of the engine was reduced from 66" to 48", about 27%, and the reduction in weight resulting from this reduction in length together with the use of 25 the sleeve valves as cylinder liners and the elimination of any poppet or rotary valve mechanism, was estimated at approximately 33%. These reductions assist materially in the attainment of two-stroke aircraft Diesel engines of less specific 30 weight than that of present gasoline aircraft engines.

Having thus described the invention, it is obvious that the objects thereof as set forth herein have all been attained. While specific embodiments of the invention have been shown and 35 described, it is understood that changes may be made in the arrangement and in the construction of the various parts without departing from the spirit or scope of the invention as expressed in the following claims.

40 I claim:

1. In an engine comprising a shaft, cylinders spaced about and parallel thereto, pistons and piston sealing means operable therewith, and means operably connecting said pistons with said 45 shaft; means for retaining said sealing means in operable position when withdrawn beyond the mouths of said cylinders and permitting said pistons (and therefore said engine) to be shorter and of less weight than would otherwise be possible, said means comprising sleeve valve members 50 serving as cylinder liners and surrounding said pistons and sealing means, and reciprocable with telescopic effect on strokes shorter than, but as frequent as and timed substantially with the 55 strokes of said pistons.

2. An engine comprising a shaft, cylinders spaced about and parallel thereto, sleeve valve members operable in said cylinders, pistons and piston rings operable within said sleeve valve 60 members, mechanism operably connecting said pistons with said shaft whereby the strokes of said pistons accompany rotation of said shaft, and means for reciprocating said sleeve valve members with strokes shorter than, but as frequent as and timed substantially with the strokes of said pistons retaining said piston rings in operable position within said sleeve valve members, even when said rings are withdrawn beyond the mouths of said cylinders, permitting said pistons (and therefore said engine) to be shorter and of less weight than would otherwise be possible.

3. A uniflow two-stroke internal combustion engine comprising a shaft, cylinders spaced about 75 and parallel thereto, cylinder heads closing the

outer ends of said cylinders, sleeve valve members operable in said cylinders, pistons operable within said sleeve valve members, mechanism operably connecting said pistons with said shaft, intake ports in said sleeve valve members and controlled by said pistons, exhaust passages adjacent said cylinder heads and controlled by said sleeve valve members, and means for reciprocating said sleeve valve members on strokes shorter than, but as frequent as and timed substantially with the strokes of said pistons.

4. An engine comprising a shaft, cylinders spaced about and parallel thereto, sleeve valve members operable in said cylinders, pistons operable within said sleeve valve members, and a 15 mechanism for the interconversion of reciprocation and rotation operably connecting both said pistons and said sleeve valve members with said shaft, the strokes of said sleeve valve members being shorter than, but as frequent as and timed 20 substantially with the strokes of said pistons.

5. An engine comprising a shaft, cylinders spaced about and parallel thereto, sleeve valve members operable in said cylinders, pistons, operable within said sleeve valve members, a wabbler mechanism operably connecting said pistons with said shaft, and means operably connecting said wabbler mechanism with said sleeve valve members for driving them with strokes shorter than, but as frequent as and timed slightly in 30 advance of the strokes of their respective pistons.

6. An engine comprising a shaft, cylinders spaced about and parallel thereto, an individual sleeve valve member operable in each of said cylinders, pistons reciprocable within said sleeve valve members, mechanism operably connecting said pistons with said shaft, and means independent of said mechanism and operably connecting said sleeve valve members with said shaft for reciprocating said sleeve valve members with 40 strokes shorter than, but as frequent as and timed substantially with the strokes of their respective pistons.

7. In an engine comprising a shaft and cylinders spaced about and parallel thereto, the combination of an individual sleeve valve member operable in each of said cylinders, pistons reciprocable within said sleeve valve members, a wabbler operably connecting said pistons with said shaft, and means for driving said sleeve valve members on strokes as frequent as and timed substantially with the strokes of said pistons, said means comprising a cam mechanism operably connecting said sleeve valve members with said shaft.

8. In a normal parallel cylinder engine having a shaft, double-ended piston members operably connected thereto, and two similar groups of cylinders facing each other: integral tubular members each serving as movable cylinder liners and sleeve valves for a pair of opposite cylinders and as a crosshead guide for the piston member operable within said pair of cylinders.

9. A two-stroke engine comprising a casing, a shaft operably mounted in said casing, cylinders in two similar groups facing each other across said casing, sleeve valve members operable in said cylinders, double-ended piston members each operable in a pair of corresponding cylinders of said groups, and mechanism for the interconversion of reciprocation and rotation operably connecting said piston members and said sleeve valve members with said shaft, the strokes of said sleeve valve members being shorter than, but as frequent as and timed substantially with the 75

- strokes of said piston members, permitting said piston members to be shorter and said engine more compact and of less weight than would otherwise be possible.
- 5 10. A two-stroke engine comprising a casing, a shaft operably mounted in said casing, cylinders facing each other across said casing, sleeve valve members operable in said cylinders, piston members operable within said sleeve valve members, and mechanism for the interconversion of reciprocation and rotation operably connecting said piston members and said sleeve valve members with said shaft, the strokes of said sleeve valve members being shorter than, but as frequent as and timed substantially with the strokes of said piston members.
- 10 11. An engine comprising a casing, a shaft operably mounted in said casing, cylinders spaced about and parallel with said shaft, sleeve valve members operable in said cylinders, pistons operable within said sleeve valve members, a wabbler operably mounted on said shaft on bearings inclined thereto, operable connections between said wabbler and said pistons, and means comprising operable connections between said wabbler and said sleeve valve members for driving said sleeve valve members and for preventing rotation of said wabbler and for holding said wabbler substantially to its true geometric motion.
- 15 12. An engine comprising a casing, a shaft operably mounted in said casing, cylinders spaced about and parallel with said shaft, sleeve valve members operable in said cylinders, pistons reciprocable within said sleeve valve members, means operably connecting said pistons and said shaft, mechanism for driving said sleeve valve members on strokes as frequent as and timed substantially with the strokes of said pistons, and means for eliminating excessive clearance from said driving mechanism.
- 20 13. An engine comprising a casing, a shaft operably mounted in said casing, cylinders spaced about and parallel with said shaft, sleeve valve members operable in said cylinders, pistons operable within said sleeve valve members, means operably connecting said pistons and said shaft, mechanism for driving said sleeve valve members from said shaft, and means for eliminating excessive clearance from said driving mechanism and comprising a piston and cylinder, a spring urging the piston outwardly from said cylinder, and a check valve for trapping oil within said cylinder.
- 25 14. In a parallel cylinder engine having a shaft and cylinders spaced about and parallel thereto, a fuel supply system comprising a cam on said shaft, fuel pump units radially disposed about and driven by said cam and extending across the heads of said cylinders, and fuel injection nozzles inserted thru said fuel pump units into said cylinder heads.
- 30 15. An engine comprising a casing, bearings supported by said casing, a shaft operably mounted in said bearings, cylinders in two groups facing each other across said casing, sleeve valve members having ports and operable in said cylinders, piston members operable within said sleeve valve members, oil control rings on said piston members, and mechanism for the interconversion of reciprocation and rotation operably connecting said piston members and said sleeve valve members with said shaft, the strokes of said sleeve valve members being as frequent as and timed in advance but substantially with the strokes of said piston members permitting said piston members to be shorter than would otherwise be possible by the telescopic effect and preventing said oil control rings from ever passing over said ports.
- 35 16. An engine comprising a shaft, cylinders spaced about and parallel to said shaft, sleeve valves operable in said cylinders, pistons operable within said sleeve valves, and means for reciprocating both said pistons and said sleeve valves upon rotation of said shaft, the strokes of said sleeve valves being shorter than, but as frequent as and timed substantially with the corresponding strokes of said pistons, said means comprising rollers operably seated in said pistons and in said sleeve valves, and a cam member fixed upon said shaft and operably engaging all of said rollers.
- 40 17. In an engine having a shaft, a double-ended piston members operably connected to said shaft, and two similar groups of cylinders facing each other: integral tubular members each serving as movable cylinder liners and sleeve valves for a pair of opposite cylinders, and as a cross-head guide for the piston member operable within said pair of cylinders, and means for driving each of said tubular members on strokes as frequent as and timed substantially with the strokes of the corresponding double-ended piston member.

EDWIN S. HALL.
